[57] CLAIM

The ornamental design for insulated cooler, as shown and described.

DESCRIPTION

FIG. 1 is a front perspective view of an insulated cooler showing my new design;

FIG. 2 is a top plan view thereof;

FIG. 3 is a side elevational view thereof, the opposite side being identical;

FIG. 4 is a front perspective view of an alternate embodiment of FIG. 1;

FIG. 5 is a top plan view of FIG. 4; and,

FIG. 6 is a side elevational view of FIG. 4, the opposite side being identical;

The undisclosed bottom views are unornamented.

FIG.1

FIG.2

FIG.3

FIG. 4

FIG. 5

FIG. 6
